UNITED STATES PATENT OFFICE.

LAWRENCE E. DARE, OF NEW YORK, N. Y.

PIPE.

No. 823,718.

Specification of Letters Patent.

Patented June 19, 1906.

Application filed February 20, 1905. Serial No. 246,363.

To all whom it may concern:

Be it known that I, LAWRENCE E. DARE, a citizen of the United States, residing in the borough of Manhattan, city of New York, in the county of New York and State of New York, have invented certain new and useful Improvements in Pipes, of which the following is a specification.

This invention relates to and has for an object to provide an improved pipe.

The object of this invention is to provide a pipe which will arrest the passage of condensation from the pipe-bowl toward the mouthpiece and which will also arrest the passage of saliva and condensed moisture from the mouthpiece into the bowl and provide suitable means for the detention of the same after it has been arrested.

In the drawings accompanying and forming a part of this specification, Figure 1 is a side view, partly in central section, of a pipe embodying a form of my improvement. Fig. 2 is a perspective view of one of the parts detached, in the present instance that part which is employed for use in the passage directly leading from the bowl of the pipe; and Fig. 3 is a similar view of the part used in the stem of the pipe.

The pipe-bowl (designated in a general way by 7) is shown as having the usual tobacco-receiving cavity 8, from which bowl there projects a stem or stem-receiving portion 9, having a draft passage-way 10, leading into a recess or chamber 11, into which the stem 12 of the pipe may be inserted. For the purpose of preventing saliva flowing from the chamber 11 into the passage 10 an upstanding tube 13 may be inserted in the passage 10 and have its end projecting into the chamber 11, so that a considerable quantity of liquid or semiliquid matter might accumulate without clogging up the draft-passage or finding access into the bowl. The condensed smoke and stray particles of saliva running into the lower portion of the stem will not only clog and foul the draft-passage, but upon running into the bowl proper of the pipe will contaminate the tobacco which is within the bowl and prevent at times the ready burning of the tobacco. It will be seen by reference to Fig. 2 that the ends 14 of the tube 13 are conoidal, which will permit their ready insertion and removal into passages of various diameters and will always insure a tight fit irrespective of the number of times the tube may be removed and in-

serted, and by having each end tapered it will be reversible, so that the user need not exercise any care as to which end he inserts after having had the tube out for the purpose of cleansing the pipe. The stem is shown as having a draft-passage 15, having its lower portion expanded into a chamber 16. In the form of pipe illustrated the end portion 17 of the stem enters the chamber 11, this being the most common mode at the present time of assembling the bowl and stem in the form of pipe illustrated.

The lower portion of the chamber 16 may be stopped by a removable dam 18, in the present instance shown in the form of a cup having side walls 19 adapted to pass up into the chamber 16 and engage the walls thereof by frictional contact. Other engagement may be provided, but in this form of pipe frictional contact will be sufficient. The cup or rather the dam portion 18 is provided with an upstanding pipe or tube 20, projecting up into the chamber 16 a considerable distance. This tube constitutes the draft-channel 80 through the chamber and dam, and any accumulation of saliva or other moisture within the chamber 16 will be held from passage downwardly through the pipe. The cup in most instances will be sufficient to receive 85 and retain moisture; but in case a large amount should be permitted to accumulate there will be no chance of its falling into the pipe-bowl until it has risen to a height sufficient to pass down the tube 20, and the dam 90 will also prevent liquid which has accumulated within the chamber 11 from passing up into the stem and so gaining access to the mouthpiece. It will be seen that the end 21 of the tube 20 nearly approaches the end 22 95 of the tube 13, and thereby bridges over the space within the chamber, and that the end 23 of the tube 20 nearly approaches to the portion 24 of the draft-channel 15, where such channel assumes its normal proportions, 100 thus bridging over the channel 16, whereby the smoke in passing from the bowl to the mouthpiece will not be forced to circulate and fill the various chambers provided for the arrest and storage of fluids. The bottom 105 portion of the cup may be provided with a knurled head 25 to enable the ready removal of the cup for the purpose of emptying the same of any accumulations and to permit the parts to be properly cleansed from time to time. The head 25 may be of less diameter 110 than the inside diameter of the chamber 11,

where it is normally located, so that it will not become foul by the condensed smoke and nicotin which will work up on the walls of the chamber 11.

5 As a further guard for preventing the passage of saliva into the pipe the mouthpiece (designated in a general way by 30) may have the orifice 31 of the channel 15 overhung by a lip 32 and have the usual depressions 33 34 10 for engagement by the teeth. The enlarged portion 35 rearward of the depression 34 will act as a guard to the orifice and in conjunction with the lip 32 will prevent the tongue of the smoker coming against the orifice 31, 15 so that saliva cannot find access to the orifice, and also the tongue will be held away from such orifice and burning will be prevented.

The parts for insertion into the channels of 20 the pipe may be made out of some suitable material; but I have ascertained by experimentation that when made of aluminium the pipe is rendered especially sanitary, for the reason that aluminium does not readily corrode by exposure to the matters which come 25 in contact with it when so employed and has but little affinity therewith, so that it will not become foul and can be readily cleansed.

Having thus described my invention, I 30 claim—

1. The combination with a bowl member having a chamber at its upper end, and a

stem having a chambered portion at its lower end with such end fitting into the end of the bowl member, of a cup member comprising a cylindrical portion closed at one end and having its other end arranged to fit into the engaging end of the stem, the cup member having an elongated tube extending from its closed end portion upward beyond the cylindrical portion into the chamber of the stem, the bore of the tube being continued through the end portion of the cylindrical part. 35 40

2. In a pipe, the combination with the 45 bowl member having its upper end chambered, and the stem having its lower end chambered and fitted into the bowl member, of an integral cup member comprising a cylindrical portion 19, having a closed end 18 50 and flange 25, whereby the member can be inserted in the lower end of the stem with the flange engaging the end portion thereof, the cup member also having an integral tube 20 extending upward from the parts beyond the 55 cylindrical portion 19 and provided with the bore 23 continuing through the end portion 18, substantially as set forth.

Signed at Nos. 9 to 15 Murray street, New York, N. Y., this 17th day of February, 1905. 60

LAWRENCE E. DARE.
